Des. 207,026

Patented Feb. 21, 1967

207,026

COORDINATE MEASURING MACHINE

Robert I. Leach, Clinton, and John H. Lanahan, Whitesboro, N.Y., assignors to The Bendix Corporation, a corporation of Delaware

Filed July 1, 1965, Ser. No. 86,021

Term of patent 3½ years

(Cl. D55—1)

FIG. 1

FIG. 2

FIG. 3

FIGURE 1 is a front perspective of the coordinate measuring machine showing our new design;

FIGURE 2 is a front elevation thereof, with the broken line showing of the base omitted for convenience of illustration; and

FIGURE 3 is a side elevation thereof.

The dominant features of our design reside in the portion shown in full lines.

We claim:

The ornamental design for a coordinate measuring machine, as shown and described.
